Inventor:

Karl Grassau.

United States Patent Office.

KARL GRASSAU, OF VIRGINIA CITY, NEVADA.

Letters Patent No. 101,456, dated April 5, 1870.

IMPROVED LASTING-MACHINE.

The Schedule referred to in these Letters Patent and making part of the same

To all whom it may concern:

Be it known that I, KARL GRASSAU, of Virginia City, county of Storey, State of Nevada, have invented an Improved Boot and Shoe Lasting Machine; and I do hereby declare the following description and accompanying drawings are sufficient to enable any person skilled in the art or science to which it most nearly appertains, to make and use my said invention and improvements without further invention or experiment.

My invention relates to an improved machine for lasting or fitting the upper leather of boots and shoes; and,

It consists of an arm or bar, the end of which is firmly fastened to the last through the insole which is in its place. This arm has attached to it a series of clamps, which hold the edges of the upper leather while they are themselves acted upon by screws which draw the leather tight across the last, and hold it while being stitched.

To more fully describe my invention, reference is made to the accompanying drawings and letters of reference marked thereon.

A is a strong arm or bar bent as shown, and fastened to the last through the insole B by nails *a a*.

The part of the bar which rests on the sole, is grooved, so as to receive the sliding end *d* of the toe clamp C, and guide it in its movements forward and back.

This clamp is moved by a screw, D, which works through the bar A, and turns in the standard L, having a shoulder to prevent its advance or retreat without moving the standard.

The two clamps E E at the sides of the ball of the foot are hinged by means of extended arms *e* to a central nut, F, which is outside the bar A, and is moved together with the clamps E to and from the sole by a screw, G, operating through the nut F.

The clamps H H, which draw the leather over the

instep, are attached to the bar A in a manner similar to the clamps E by arms *f*.

Through the arms *e* and *f* are screws I and J, with nuts which serve to bring the clamps nearer together, and so stretch the leather as much as desired.

The clamps are all constructed with a movable and a fixed jaw, the fixed jaw being a part of the bars *d*, *e*, and *f* respectively, and a screw-bolt through these and the movable jaws serves to operate the latter.

The inner surfaces of the jaws are roughened, so that they will hold the leather firmly.

The operation of my machine is as follows:

The insole is placed upon the last, and the bar A is fastened to the last by the pins *a a*. The upper leather is then clamped by the jaw C, and the screw D turned so as to draw it down tight over the toe of the last. The leather is then seized by the clamps E E at the sides of the ball of the foot, and the screw G is turned so as to draw the leather beyond the edges of the sole. This being accomplished, the nut on the screw I is turned and the leather drawn together under the sole. The counter is then drawn down to its place, and the clamps H H adjusted to the leather, and the nut on the screw J moved so as to draw the leather under the sole, when it is ready to be stitched.

Having thus described my invention,

What I claim as new, and desire to secure by Letters Patent, is—

1. The combination of the clamp C, provided with the standard L, with the screw D and bar A, arranged to operate substantially as described.

2. In combination with the clamps E, the bar A, so constructed as to form a point of support for the screw G, substantially as described.

In witness whereof I hereunto set my hand and seal.

Witnesses: KARL GRASSAU. [L. S.]
